(57) **CLAIM**

I claim the ornamental design for a bottle caddy, as shown and described.

DESCRIPTION

FIG. 1 is a front isometric view of my new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

A view of the design bottom side has been omitted, as the bottom of the design is flat and devoid of surface ornamentation.

The broken lines are for illustrative purposes only and form no part of the claimed design.
